To all whom it may concern:

Be it known that we, Herbert Morley, a subject of the King of Great Britain and Northern Ireland and a resident of Detroit, in the county of Wayne and State of Michigan, Lawrence H. Wilson, and Herbert L. Davies, the latter two being citizens of the United States and residents of Grosse Pointe and Detroit, respectively, in the county of Wayne and State of Michigan, have invented a new, original, and ornamental Design for a Refrigerator Cabinet or Similar Article, of which the following is a specification, reference being had to the accompanying drawings constituting a part thereof.

Fig. 1 is a perspective view of the refrigerator, showing our design;

Fig. 2 is a front elevational view;

Fig. 3 is a fragmentary side elevational view; and

Fig. 4 is a plan view of the front portion thereof, shown broken away.

Our new design for a cabinet is shown as embodied in a refrigerator cabinet and is characterized by the widely rounded front side, top front and top side edges, and by the slightly curved top and by the curve of the door which blends with the curved corners and edges of the cabinet.
